UNITED STATES PATENT OFFICE

163,861

WATCHCASE

Arthur J. Geoffrion, Manhasset, N. Y.

Application August 31, 1950, Serial No. 12,003

Term of patent 7 years

(Cl. D42—8)

To all whom it may concern:

Be it known that I, Arthur J. Geoffrion, a citizen of the United States, residing at Manhasset, in the county of Nassau, State of New York, have invented a new, original, and ornamental Design for Watchcases, of which the following is a specification, reference being had to the accompanying drawing, forming a part hereof.

Fig. 1 is a face view of a watchcase, showing my new design;

Fig. 2 is a side elevational view thereof; and

Fig. 3 is an end elevational view thereof.

The essential features of my design for a watchcase reside in the ornamentation of the attachment end members of the watchcase.

I claim:

The ornamental design for a watchcase, substantially as shown and described.

ARTHUR J. GEOFFRION.
